Attorneys.

UNITED STATES PATENT OFFICE

102,112

DESIGN FOR A RADIATOR ORNAMENT OR SIMILAR ARTICLE

Alexis V. Lapteff, Detroit, Mich., assignor to
Briggs Manufacturing Company, Detroit, Mich.,
a corporation of Michigan

Application March 16, 1936, Serial No. 61,656

Term of patent 3½ years

To all whom it may concern:

Be it known that I, Alexis V. Lapteff, a citizen of Russia, residing at Detroit, county of Wayne, State of Michigan, have invented a new, original, and ornamental Design for a Radiator Ornament or Similar Article, of which the following is a specification, reference being had therein to the accompanying drawing, forming a part thereof, in which

Fig. 1 is a top plan view of the design embodying my invention; and

Fig. 2 is a perspective view thereof.

I claim:

The ornamental design for a radiator ornament or similar article, substantially as shown.

ALEXIS V. LAPTEFF.
